LUBRICATING DEVICE

Filed Aug. 23, 1926

FIG. -2-

By *Llewellyn Bonham,
F. K. Fassett,*

Attorney

UNITED STATES PATENT OFFICE

LLEWELLYN BONHAM, OF OXFORD, OHIO

LUBRICATING DEVICE

Application filed August 23, 1926. Serial No. 130,781.

This invention relates to lubricating systems for automobiles, of the type wherein various journals requiring lubrication are connected by tubes to a supply of oil, a given 5 quantity of oil being forced thru this system of tubes periodically to lubricate the journals.

Lubricating systems of the kind referred to are not new. But the present invention is an improvement over previous devices of 10 the kind. One of the principal objects of my device is to automatically distribute a measured quantity of oil among the several journals connected to the system at predetermined intervals, and another principal object 15 is to insure replenishment of the supply of oil before there is any danger of the supply becoming exhausted. Another object is to insure the cleanliness of the oil supplied to the system. Still another object is to time the 20 periods when the device operates by the operation of the automobile motor, so that the frequency with which the journals are lubricated shall depend upon the amount the journals have been used, measured by the amount 25 the motor has been used.

I shall now describe my invention in detail, referring to the accompanying drawing, in which,

Fig. 1 illustrates an internal combustion 30 motor of the kind used on automobiles;

Fig. 2 is an elevational view of the mechanism of my device for periodically sending oil thru the system of tubes to the journals to be lubricated. This view is supposed to 35 show the parts as the observer would see them were he in the crank case of the motor. Most of the intervening wall of the crank case is broken away, however, to exhibit the parts; and

Fig. 3 is a view looking down into the box containing the mechanism shown in the upper part of Fig. 2, the cover of the box having been removed. As far as possible the drawings are diagrammatic.

Referring first to Fig. 1, the crank case 40 of the motor is indicated by the numeral 10. At the left hand side of the motor an oil reservoir 11 is cast or otherwise formed, integral with the crank case 10. The cam shaft of the motor is shown at 12, and this

shaft carries a worm 13 enmeshed with a worm-gear 14. This worm-gear is mounted on a shaft which rotates in a bearing 15, secured to the crank case 10. The other end of the shaft, which shaft is not seen, carries 55 a sprocket wheel on which runs a chain 16. This chain runs a sprocket wheel mounted on a shaft 17 projecting thru the wall of the box 18, secured to the top of the reservoir 11. The two sprocket wheels are not shown in 60 the drawings, being concealed by the chain, but the chain sufficiently indicates how the shaft 17 is rotated by the cam shaft 12 of the motor. As is well known, and as is the universal practice, the cam shaft is geared to the 65 crank shaft of the motor and rotates in synchronism therewith, in the usual way.

Referring now to Figs. 2 and 3, where the fragments of the crank case seen in these figures are indicated by the numeral 10, it 70 would be seen that the oil reservoir 11 is connected to the crank case by a vertical duct 20. The upper end of this duct opens into the reservoir 11, and the lower end of the duct connects to the crank case thru an opening or 75 port 21. Oil is poured into the reservoir thru a pipe 22 having a funnel shaped upper end 23. To replenish the oil in the crank case the oil is poured into this funnel 23, and it will be seen that no oil will reach 80 the crank case until the reservoir 11 is practically filled with oil. Then oil from the reservoir will overflow into the duct 20 and enter the crank case thru the port 21. As the supply of oil in the crank case must be 85 replenished more often than that in the reservoir 11, and as motorists are compelled to give proper attention to the oil in the crank case, or come to grief, it is seen that by compelling the motorist to fill the crank case thru the reservoir 11, an ample supply 90 of clean oil is insured at all times in the reservoir 11.

The tube 30 connects to the system of tubes whereby oil is distributed to the various journals to be lubricated. As this system of tubes is no part of my invention, and as it is well known in the art, it is not necessary for me to illustrate the tubes and journals. Oil is drawn from the reservoir 11 by a 95

double acting pump 31 situated in the reservoir, and by means of mechanism which I shall presently describe the piston of the pump is moved downwardly periodically by 5 power supplied by the motor, thereby expelling oil from the cylinder which was drawn in at the last up stroke of the piston. The piston is then freed from the motor and is raised by the spring 32, drawing a charge 10 of oil thru the intake 33. The discharge pipe 30 is provided with a compression chamber 34, and it is to be understood that the pump is provided with the necessary and usual check valves.

15 I shall now describe the mechanism, including an electro-mechanical clutch, whereby the pump is operated by the motor. The shaft 17, see Fig. 3, rotates in a bearing 40 carried by one wall of the box 41. This 20 shaft, it will be remembered, is constantly rotated by the cam shaft 12 of the motor. On its inner end this shaft carries a disk 42, preferably of non-magnetic metal, which disk in turn carries a plate 43 of iron or 25 steel. The disk 43 serves as a back strap or yoke for a series of electromagnets 44, of which there are four in the present case. The poles of these magnets are enlarged by plates 45, secured thereto. A stud 46 is secured in the wall of the box opposite to 30 that which carries the bearing 40, the axis of this stud being in alignment with the axis of the shaft 17. Mounted to rotate on this stud is a disk 47, made of iron or steel, and 35 fixed to this disk, so that it will rotate in unison therewith, is a pinion 48 which meshes with a rack 49, formed on the piston 50 of the pump. Preferably, the coils of the electro-magnets 44 are connected in series and 40 one end of this series is grounded by being connected to the plate 43 (Fig. 3), or some other portion of the metallic structure. The other end of the series is connected to a ring 51, which is mounted on the hub of the disk 42, but insulated therefrom. A brush 52 is 45 pressed against the ring 51 by a spring, and this brush is connected by a conductor 53 (Fig. 3) with one terminal 54 of an electric switch. (Fig. 2.) The other terminal of 50 this switch, 55, is connected by a conductor 56 to a source of current, in the present case a generator 57 (Fig. 1), which is operated by the motor thru a belt or chain 58. The other terminal of the generator is grounded 55 on the frame of the generator in the usual way.

The poles or plates 45 are arranged to revolve quite close to the disk 47, and the disk is allowed a small amount of play parallel to 60 the axis on which it rotates. Thus when the magnet becomes energized upon closing the switch, the disk 47 is attracted to the poles 45 and the disk becomes coupled to the poles magnetically. At the end of the 65 first revolution of the disk 47, the switch is

automatically opened and the disk thereby released from the poles of the magnet. This revolution of the disk 47, and the consequent revolution of the pinion 48, having moved the piston of the pump to the bottom of the cylinder, oil contained in the cylinder is forced out of the pump thru the tube 30 to the various journals to be lubricated. Upon the release of the clutch the spring 32 returns the piston to its uppermost position, which is that shown in Fig. 2.

I shall now describe the mechanism for automatically closing the switch at predetermined intervals during the operation of the motor. The disk 42 carries on its periphery a single tooth 60 (see Fig. 2), and at each revolution of the disk this tooth engages in one of a plurality of notches 61 in the periphery of a wheel 62 and moves said wheel a fraction of a revolution. Between each two notches 61 the periphery of the wheel 62 is curved to fit the cylindrical portion of the disk 42. Thus over-rotation of the wheel 62 is prevented. In brief, the disk 42 and wheel 62 are in effect the first and second members 90 of a counter. In other words, since the wheel 62 has ten notches 61, this wheel is in effect the tens wheel of a counter. A wheel 63, united to the wheel 62 by pins 64, and having a single tooth like that of the disk 42, meshes 95 with a ten toothed wheel 65, similar to the wheel 62. A one toothed wheel 66, united to wheel 65, meshes with a ten toothed wheel 67, and a one-toothed wheel 68, united to wheel 67, meshes with a ten toothed wheel 100 69. Thus by a well known form of intermittent gearing, the shaft 17 is connected to the wheel 69, so that the wheel 69 is rotated one-tenth of a revolution each time the shaft 17 completes a predetermined number of revolutions. It is obvious, therefore, that the wheel 105 69 is rotated one revolution, step by step, during the time the shaft 17 rotates ten times said predetermined number of revolutions. In practice I prefer to have the ratio of the 110 worm 13 to the worm-gear 14 such that when the motor is running at about its average speed the shaft 17 will make one revolution each two seconds. With this arrangement it is seen that the wheel 62 turns one-tenth of 115 a revolution in one-fifth of a second. It will also be seen that when the time comes for the wheel 69 to move, it also will turn one-tenth of a revolution in one-fifth of a second. In other words, for the time being the wheels 120 62 and 69 move in unison. The wheel 69 carries a stud of pin 70, which during one of the movements of the wheel closes the switch. The wheels of this intermittent gearing rotate on studs 71 and 72, which studs are supported by a frame 73 attached to one of the 125 walls of the box 41.

I shall now describe the switch and its operation. A horizontal rock shaft 80 in the upper part of the box 41, has secured to it 130

an arm 81, which arm carries the metal blade 82 whereby the terminals 54 and 55 of the switch are connected. The arm 81 may be composed of insulating material, or, if the arm is metal, the blade must be insulated from the arm. An arm 83 is also secured to the rock shaft 80, the end of this arm extending into the path of the pin 70, so that during the movement of the wheel 69 one-tenth of a revolution the pin 70 will engage and move the arm, thereby rocking the shaft 80 and throwing the switch blade 82 into the switch terminals 54 and 55. In other words, during this particular movement of the wheel 69 the switch is closed, and it is seen that the closing of the switch is effected by power supplied by the motor. The relative positions of the pin 70, the axis 71, upon which the wheel 69 rotates, and the rock shaft 80, are such that by the time the wheel 69 has rotated the one-tenth of a revolution which closes the switch, the end of the arm 83 will have swung out of the path of the pin 70, and the pin will have passed beyond the path of movement of the end of the arm, so that the pin will not interfere with the return of the arm when the switch is opened. The switch is opened by a pin 84 projecting from the periphery of the disk 47, which pin engages the end of an arm 85 secured to the rock shaft 80. The rock shaft 80 is moved somewhat farther than the pin 84 moves it, by a spring 86, one end of which spring is attached to one end 35 wall of the box 41, the other end being attached to an arm 87 secured to the rock shaft. As is seen in Fig. 2, the line of tension of this spring is above the center of the shaft 80, and tends to move the arm 87 toward the stop pin 88 extending from the wall of the box 41. This spring also serves the purpose of causing a quick opening of the switch. When the switch is closed the arm 87 is far enough down so that the line 40 of tension of the spring is slightly below the center of the shaft 80 and therefore the spring tends, slightly, to keep the switch closed. It is not necessary to utilize the spring in closing the switch, as one-fifth of 45 one second, during which the switch is closing, is quick enough, considering the low voltage of the current employed. The stroke of the piston is sufficient to cause the disk to rotate one revolution, and the parts are so proportioned that when the piston is in its uppermost or home position the pin 84 is where it appears in Fig. 2, which is out of the path of the arm 85. The disk is rotated counter-clockwise by the motor, and after it is released from the motor by opening of the switch, the spring 32 rotates the disk clockwise to its home position. A push button 90 is provided, whereby the switch can be closed by pressing down the arm 87 manually after the motor has started. This is to be used in case the automobile has been standing idle for some time and it is desired to lubricate the journals at the beginning of a trip. If desired this button might be connected by a suitable means to a button 70 on the instrument board of the car.

As the function and operation of each of the parts of my device has been described, a general summary of the operation of the device is unnecessary. It is evident that the structural details of the device may be modified in various ways without departing from the spirit of my invention, so it is to be understood that the structure shown is merely illustrative of one embodiment of my invention. I have shown only one pin 70 in the wheel 69, but two may be put in and the pump caused to act twice as often as when one pin is used. I like to provide for operating the pump at the end of each seventy-five miles of travel of the automobile, but this varies by changing the ratio of the worm gear 13-14. By connecting the electrical equipment of my device to the generator I avoid the possibility of injury should the motor be stopped for a long time with the switch closed. In case it is connected to some constantly active source of current, for example, the battery of the ignition system, it should be connected behind the ignition switch, so it will be cut off from the battery when the ignition switch is opened to stop the motor.

What I claim as my invention is as follows:

1. In a lubricating system for an automobile propelled by an internal combustion motor having a crank-case to contain oil, which automobile has journals to be lubricated: a reservoir to contain oil, having a pipe into which oil is poured, and having an overflow duct leading to said crank-case, this being the means whereby oil is introduced into the crank case, a pump whereby oil from said reservoir is forced to said journals, means for operating said pump, and means for setting said pump-operating means into operation for a limited time each time said motor completes a predetermined number of cycles of operation, the pump being thereby set in operation a plurality of times during each period that the motor can safely be operated without replenishing the oil in the crank-case.
2. In a lubricating system for an automobile propelled by an internal combustion motor having a crank-case to contain oil, which automobile has journals to be lubricated: a reservoir to contain oil, having a pipe into which oil is poured, and having an overflow duct leading to said crank-case, this being the means whereby oil is introduced into the crank case, a pump whereby oil from said reservoir is forced to said journals, electro-mechanical means for oper-

ating said pump, and means for setting said pump-operating means into operation for a limited time each time said motor completes a predetermined number of cycles of operation, the pump being thereby set in operation a plurality of times during each period that the motor can safely be operated without replenishing the oil in the crank-case.

3. In a lubricating system for an automobile propelled by an internal combustion motor having a crank-case to contain oil, which automobile has journals to be lubricated: a reservoir to contain oil, having a pipe into which oil is poured, and having an overflow duct leading to said crank-case, this being the means whereby oil is introduced into the crank case, a pump adapted to draw oil from said reservoir to be sent to said journals, means for operating said pump, means for setting said pump-operating means in operation each time the motor completes a predetermined number of cycles of operation, and means for limiting the duration of the pump's operation, the pump being thereby set in operation a plurality of times during each period that the motor can safely be operated without replenishing the oil in the crank-case.

4. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a train of gearing driven by the motor, and means whereby said gearing connects said clutch with a source of electrical energy periodically.

5. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a switch to connect said clutch to a source of electrical energy, a train of gearing driven by the motor, and means whereby said train closes said switch each time the motor completes a predetermined number of cycles of operation.

6. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a switch to connect said clutch to a source of electrical energy, a train of intermittent gearing, the first member of which is rotated by the motor, the last member of said train, which for the time being is rotating at the velocity of the

first member, closing said switch at the completion of each cycle of said train.

7. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a switch to connect said clutch to a generator of current driven by the motor, and a train of intermittent gearing, the first member of which is rotated by the motor, the last member of said train, which, for the time being, is rotating at the velocity of the first member, closing the switch at the completion of each cycle of said train.

8. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a switch to connect said clutch to a generator of current driven by the motor, a train of intermittent gearing, the first member of which is rotated by the motor, the last member of said train, which, for the time being, is rotated at the velocity of the first member, closing the switch at the completion of each cycle of said train, and means whereby the switch is opened by the motor when the motor has operated a predetermined number of cycles after the closing of the switch.

9. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a switch to connect said clutch to a source of current, and a train of intermittent gearing, the first member of which is rotated by the motor, the last member of said train, which, for the time being, is rotating at the velocity of the first member, closing the switch at the completion of each cycle of said train.

10. In combination with an internal combustion motor, a reservoir adapted to contain oil, a pump adapted to draw oil therefrom, means comprising the motor for operating the pump, and means for connecting the pump to the motor intermittently, said means comprising an electro-magnetic clutch, a switch to connect said clutch to a source of current, a train of intermittent gearing, the first member of which is rotated by the motor, the last member of said train, which, for the time being, is rotating at the velocity of the first member, closing the switch at the completion of each cycle of said train, and means whereby the switch is opened by the motor when the motor has operated a predetermined

number of cycles after the closing of the switch.

11. In a lubricating system for an automobile propelled by an internal combustion motor having a crank-case to contain oil, which automobile has journals to be lubricated: a pipe into which oil to supply the crank-case is poured, which pipe leads to a reservoir, an overflow conduit in said reservoir leading to the crank-case, the reservoir retaining sufficient oil to lubricate said bearings a plurality of times, and means for periodically lubricating said journals with oil from said reservoir.

12. In combination with an internal combustion motor having a crank-case containing oil, a reservoir having an inlet for oil and an overflow duct leading to the crank-case, the crank-case being thereby supplied with oil; a pump adapted to draw oil from said reservoir, means for operating said pump, and means for setting the pump operating means in operation each time the motor completes a predetermined number of cycles of operation, the pump being thereby set in operation a plurality of times during each period that the motor can safely be operated without replenishing the oil in the crank-case.
